(57) **CLAIM**

The ornamental design for a jacket as shown and described.

DESCRIPTION

FIG. 1 is a front, right side perspective view of a jacket showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In FIGS. 1-7, the thinner wider spaced broken lines on the jacket showing the collar, zipper pulls, and inside of the jacket, form no part of the claimed design. The heavier evenly spaced broken lines along the surfaces of the jacket depict claimed stitching. The applied stippling technique in the drawings shows shading that defines the contours of the jacket and does not reflect a particular surface ornamentation or material.
